UNITED STATES PATENT OFFICE.

FREDERICK H. MOORE, OF MELROSE, MASSACHUSETTS.

PAPER-DISPENSING HOLDER.

1,242,019.

Specification of Letters Patent.

Patented Oct. 2, 1917.

Application filed October 19, 1916. Serial No. 126,537.

To all whom it may concern:

Be it known that I, FREDERICK H. MOORE, a citizen of the United States, residing at Melrose, in the county of Middlesex and 5 State of Massachusetts, have invented new and useful Improvements in Paper-Dispensing Holders, of which the following is a specification.

This invention relates to a holder adapted 10 to contain a pack of independent sheets of toilet or other paper, and to project the sheets one at a time from the holder.

The invention has for its chief object to provide a holder adapted to insure the delivery of only one sheet at a time, and to so support the sheets that, while the sheet forming the front side of the pack is readily separable from the means supporting it in the holder, the next sheet will remain in 20 position until it in turn becomes the front sheet.

The invention consists in the improvements which I will now proceed to describe and claim.

25 Of the accompanying drawings forming a part of this specification,—

Figure 1 represents a side view of a holder embodying the invention.

Fig. 2 represents a section on the line 2—2 30 of Fig. 1.

Fig. 3 represents a section on the line 3—3 of Fig. 2.

Fig. 4 represents a fragmentary perspective view showing the V-shaped arm, hereinafter described, which supports the paper 35 pack.

Fig. 5 represents a perspective view of a paper pack adapted, to engage the above-mentioned arm.

40 Fig. 6 represents a perspective view of the feed roll and its carrier, hereinafter described, detached from the casing.

The same reference characters indicate the same parts in all of the figures.

45 The casing of my improved holder includes a back 12 adapted to be secured preferably in a vertical position to a wall or other support, and a box portion 13 which is hinged at 14 to the back and is adapted to 50 swing toward and from the latter, said portion 13 being open at its inner side, so that, when swung outwardly, its contents are exposed, and, when swung inwardly against the back as shown by Figs. 1, 2 and 3, it 55 operates with the back in forming an in-

closure, suitable means being employed for detachably securing the swinging end of the box portion 13 to the back.

The casing is provided, near the end represented in the drawings as the upper end, 60 with means for engaging and supporting a pack 15 composed of superimposed independent sheets of toilet or other paper, said means being preferably embodied in an arm 16 attached at one end to the back 12 and 65 projecting therefrom toward the front of the casing. The arm 16, which is preferably of sheet metal, is V-shaped in cross section so that it has a salient side and a re-entrant side, the salient side facing up- 70 wardly as indicated by Fig. 4, and acting as a wedge to split the upper end portions of the sheets of the pack 15 as hereinafter described.

In one end portion of the pack I have 75 formed a V-shaped slot 17, Fig. 5, extending through the pack from front to rear, the salient side of the slot being relatively near one end of the pack so that one end portion of each sheet is adapted to be split by 80 the arm 16.

The pack is engaged with the arm 16 while the box portion 13 is displaced, the main portion of the pack extending downwardly from said arm, and the rear side of 85 the pack being supported by the back 12.

The lower end of the box portion 13 is provided with a delivering outlet 18 through which the sheets may be projected one at a time. Said outlet is preferably at 90 the front side of the portion 13, and the back 12 is preferably provided with an inclined deflecting plate 19 which deflects the lower portion of the pack to the outlet 18, as indicated by Figs. 1 and 3. 95

Located within and hinged to the box portion 13 is a feed roll carrier composed of two swinging arms 20 and a neck portion 21 connecting said arms. The hinge connection between the carrier and the portion 13 100 is preferably provided by a shaft 22 journaled in bearings in opposite sides of the portion 13 and provided at one of its projecting ends with a knob or handle 23 located outside of the casing whereby the 105 shaft may be rotated. Said shaft passes loosely through orifices in the arms 20, and the outer end portions of said arms at one side of the shaft are longer than the inner end portions at the opposite side, so that 110

said outer end portions are adapted to be pressed by their own weight toward the back of the casing.

24 represents a feed roll, the shaft 25 of which is journaled in bearings in the swinging ends of the carrier arms 20, the arrangement being such that the said arms and feed roll are pressed by their own weight and by the weight of the outer end portions of the arms toward the back 12, and against the front side of the pack 15.

I have provided means for manually rotating the feed roll and thus causing it to pull the front sheet of the pack away from the arm 16 and project said sheet through the outlet 18, the pull exerted on the front sheet by the frictional drag of the feed roll causing the wedge-shaped arm 16 to split the upper end portion of the sheet and thus 20 detach it from the arm.

I prefer, as the means for rotating the feed roll, a sprocket wheel 27 attached to the shaft 22, a sprocket wheel 28 attached to the shaft of the roll 24, and a sprocket chain 29 connecting the wheels 27 and 28. If desired, however, the shaft 25 of the feed roll may be extended through a slot 30 in one side of the box portion 13 and provided with a suitable operating knob or handle, so that the roll 25 may be rotated by a force applied directly to it instead of being applied indirectly through the sprocket wheel and chain above described. I prefer the first-described means for rotating the roll, however, because the roll rotated by said means cannot be pressed against the pack by any force except gravity, so that it is impossible for the operator to exert sufficient force to cause the detachment of more than one sheet at a time 40 from the pack.

The V- or wedge-shaped arm 16 co-operates with the pack having the V-shaped slot 17 in insuring the detachment of only one sheet at a time, said arm presenting a wide bearing for the upper side of the slot 17 which is sufficient to prevent an inner sheet from being split by the frictional drag of the outer sheet upon it. The described form of the arm 16 and its wide bearing on the 50 edges of the slot 17 in the pack, enable a single arm to firmly support a pack and prevent it from swinging edgewise.

Backward rotation of the feed roll 24 may be prevented by a ratchet 32 attached to the roll and a pawl 33 attached to the carrier and engaging said ratchet.

The box portion 13 may be provided with a sight opening 34 exposing a portion of one edge of the pack 15 and enabling the operator to determine when the pack has been entirely removed.

What I claim is:—

1. A dispensing holder for paper sheets, comprising a casing having internal means 65 at one end for engaging one end portion of

a pack of sheets, a back arranged to support the inner side of said pack and a delivering outlet at the opposite end, a roll carrier pivoted in said casing and composed of a pair of parallel arms and a connecting neck, a hinge connection between said carrier and the casing, permitting the outer end portions of the arms to swing by their own weight toward the back of the casing, and a feed roll journaled in the outer end portions 75 of the arms and pressed by its own weight and by the weight of the said arm portions toward the back of the casing and against the front side of the pack therein, means being provided for rotating said roll and thereby projecting the front sheet of the pack through said outlet.

2. A dispensing holder for paper sheets, comprising a casing having internal means at one end for engaging one end portion of a 85 pack of sheets, a back arranged to support the inner side of said pack, and a delivering outlet at the opposite end, a roll carrier within said casing and composed of a pair of parallel arms and a connecting neck, a shaft 90 journaled in the sides of the casing near the front thereof and passing loosely through orifices in said arms, so that the outer end portions of the arms are permitted to swing by their own weight toward the back of the 95 casing, said shaft being provided with an external operating handle, a feed roll journaled in the outer end portions of the arms and pressed only by its own weight and by the weight of the said arm portions toward 100 the rear side of the casing and against the front side of a pack therein, and connections between the said shaft and roll whereby rotary movement may be imparted from the shaft to the roll without increasing the pressure of the roll on the pack, to project the front sheet of the pack through said outlet.

3. A dispensing holder for paper sheets, comprising a casing having internal means at one end for engaging one end portion of a 110 pack of sheets, a back arranged to support the inner side of said pack, and a delivering outlet at the opposite end, a roll carrier within said casing including arms and a connecting neck, a shaft journaled in the sides 115 of the casing near the front thereof and engaged with said carrier to permit the arms thereof to swing by gravity toward the back of the casing, said shaft being provided with an external operating handle and with a 120 sprocket wheel located within the casing, a feed roll journaled in said arms and pressed by gravity against the front side of said pack, said roll being provided with a sprocket wheel, and a chain connecting the 125 sprocket wheels of the shaft and roll.

4. A dispensing holder for paper sheets, comprising a casing having a back adapted to support the inner side of a pack of sheets, an arm V-shaped in cross section attached to 130

said back and arranged to transfix the upper end portion of said pack and prevent the pack from swinging edgewise, the salient side of said arm facing upwardly and acting as a wedge, said holder being provided at its lower end with a delivering outlet, and sheet-projecting means engaging the front side of the pack and adapted to pull the front sheet

thereof downwardly and project it through said outlet, a downward pull on said sheet 10 causing the V-shaped arm to split the upper end of the sheet.

In testimony whereof I have affixed my signature.

FREDERICK H. MOORE.
